UNITED STATES PATENT OFFICE.

WILLIAM J. BUECHLER, OF CRAWFORDSVILLE, INDIANA.

AUTOMATIC LATCH-RELEASING MECHANISM.

1,323,741.

Specification of Letters Patent.

Patented Dec. 2, 1919.

Application filed May 21, 1917. Serial No. 170,046.

To all whom it may concern:

Be it known that I, WILLIAM J. BUECHLER, a citizen of the United States, and a resident of Crawfordsville, in the county of 5 Montgomery and State of Indiana, have invented a certain new and useful Improvement in Automatic Latch-Releasing Mechanism, of which the following is a specification.

10 The present invention relates to an automatic latch releasing mechanism adapted for use on windows, and has for an object to provide means for direct contact with the object to be locked and which may be released electrically.

15 A still further object of the invention is to provide improved electrical devices for use in the circuits employed, for retaining the sashes of the windows open at various 20 heights and for automatically releasing the sashes when the circuits are closed.

The above, and various other objects and advantages of this invention will be in part described, and in part understood, from the 25 following detailed description of the present preferred embodiment, the same being illustrated in the accompanying drawings wherein:

Figure 1 is an inner side elevation of a 30 window showing a sash partly raised, the view also showing diagrammatically one system of circuits which may be employed, and showing partly in section one of the window operating devices.

35 Fig. 2 is an outer end elevation of one of the window operating devices.

Fig. 3 is a vertical section taken longitudinally through the same substantially on the line 3—3 of Fig. 2.

40 Fig. 4 is a horizontal section taken longitudinally through the window operating device substantially on the line 4—4 of Fig. 3.

Fig. 5 is a detail sectional view of the 45 automatic latch for retaining the window-operating device inoperative and for maintaining the circuits open after energizing the device.

Referring to the drawings, A designates a 50 window casing of any approved type provided therein with vertically movable sashes B of the usual construction, and which are adapted to normally fall by gravity into closed position. Carried upon one side of 55 the casing A and preferably seated therein, is a sash-controlling device comprising a cas-

ing 10 positioned at a suitable distance from the lower end of the casing A, and which is preferably of elongated flat formation.

Arranged longitudinally near the top and 60 within the casing 10 is a locking lever 11 which projects at opposite ends through the opposite ends of the casing 10. A friction shoe 12, of rubber or the like, is carried upon the inner end of the lever 11 and is 65 adapted for binding engagement against the adjacent edge of the sash B. When in locking position, the lever 11 is adapted to extend substantially horizontally through the casing 10, and the friction shoe 12 is 70 preferably inclined inwardly away from the sash B to release the latter when the inner end of the lever is raised. The lever 11 is pivoted upon a pin 13 at a point nearer the inner end of the lever than the outer end thereof, 75 the pin 13 being secured transversely through the casing for supporting the lever. The casing 10 is provided upon its outer end with a sliding bolt or latch 14 which is 80 slidably and horizontally mounted in a bracket 15, and is provided with a spring 16 arranged between the bracket and the bolt to normally urge the latter at its free end against the projecting outer extremity of the lever 11 when the latter is in a horizontal 85 position, as shown in Figs. 3 and 4. The outer extremity of the lever 11 is of such width, vertically, that when the inner end of the lever 11 is raised out of engagement with the sash B, the bolt 14 is released, and the 90 latter is adapted to snap over the upper edge of the lever 11 to retain it positively in raised or releasing position.

For the purpose of adjustably holding the outer end of the lever 11 in position when 95 raised, a set screw 17 is threaded downwardly through the top of the casing 10 and is provided upon its lower extremity with a fixed contact point adapted to engage a movable contact point carried upon the free end 100 of a leaf spring 18, the latter being mounted upon the outer end and upper edge of the lever 11. When released by the bolt 14, the lever 11 is adapted to be normally raised at its outer end and yieldingly held in such 105 position by the provision of a spring 19 having one end fixed within the bottom of the casing 10, and its opposite end secured to the inner end of the lever 11 for urging the latter downwardly.

110 Electrically actuated means is provided in the casing 10 for moving the lever 11 into

releasing position, the means in the present instance comprising a magnet or solenoid 20 arranged vertically in the casing 10 beneath the outer end of the lever 11, and 5 having its pole piece arranged in alignment beneath an armature 21 carried upon the lower edge of the lever 11.

A preferred arrangement of the electric circuit is shown in Fig. 1 with respect to 10 one window, and wherein wires 22 and 23 lead from any suitable source of electric energy, such as the exciter shown at 24, the wire 22 leading directly to the set screw 17 in the top of the casing 10. The opposite 15 lead or wire 23 is connected to an automatic circuit closer of any approved type and designated at 25, a fuse 26 being interposed in the lead 23. A wire 27 leads directly to one side of the magnet 20 within the 20 casing 10, and a wire 28 leads from the magnet 20 to the pivot pin 13 of the locking lever 11. It will thus be evident that when the circuit is closed, the latter will be closed to the elements as above-pointed out for 25 energizing the magnet 20 to draw the outer end of the lever 11 downwardly to release the shoe 12 from the side of the sash B. The sash B, by its weight, is adapted to fall into closed position, and any suitable 30 means may be employed for regulating the fall. The outer end of the lever 11 is drawn downwardly out of the path of the bolt 14, and the spring 16 thereof urges the bolt across the vertical path of the lever 11, thus 35 holding the lever 11 in releasing position and against the tension of spring 19. This downward movement of the outer end of the lever 11 moves the spring 18 away from the fixed contact 17, and breaks the above-described 40 circuit, so that even though the circuit closer 11 maintains its portion of the circuit closed, the circuit is broken between the fixed and movable contacts in the casing 10 and thus a loss in current consumption is 45 avoided. To again open the sash B it is only necessary to raise the same to the desired height and withdraw the latch 14, the circuit closer 25 being open, to release the locking lever 11 when the latter is drawn 50 downwardly at its inner end by the spring 19 and binds the shoe 12 against the adjacent edge of the sash B. This readjustment of the lever 11 into locking position brings the fixed and movable contacts in 55 the casing 10 into engagement with each other to complete that portion of the circuit which passes through the casing.

It is of course understood that various changes may be made in the details of con-

struction of the above-specifically described 60 embodiment of this invention without departing from the spirit thereof, and being restricted only by the scope of the following 65 claims.

I claim:—

1. In an automatic latch releasing mechanism, the combination of a casing, a latch lever pivoted between its ends intermediately in the casing and projecting at one end from the casing for engagement with an 70 element to be locked, said lever yieldingly seeking the locking position, a magnet arranged to attract the other end of said lever for swinging said lever into releasing position, a stop element secured in insulated 75 relation to the casing in the path of the said other end of the lever and opposite the magnet for limiting the swinging of the lever in the direction of its locking movement, releasable means adapted to hold the lever in 80 released position, and an electric circuit including in series the stop element, the lever and the magnet for energizing the latter to release the latch lever and open the circuit through said stop element, said releasable 85 means being adapted to hold the lever in the released position with the circuit open.

2. In an automatic latch releasing mechanism, the combination of a casing, a latch lever pivoted between its ends intermediately in the casing and projecting at one end from the casing for engagement with an element to be locked, a spring in the casing 90 engaging the latch lever for urging said projecting end thereof in one direction to bind against the element, a magnet in the casing opposite the other end of the latch lever and adapted when energized to swing the lever against the tension of the spring 95 into releasing position, a stop element secured in insulated relation to the casing in the path of the said other end of the lever and opposite the magnet for limiting the swinging of the lever under the tension of the spring, a manually releasable spring 100 bolt carried on the casing and normally urged against the side of the lever and adapted to snap over the edge of the lever when actuated by the magnet for holding the lever in released position, and an electric circuit including in series the stop element, the lever and the magnet for energizing the latter to release the latch lever 105 and open the circuit, said bolt being adapted to snap over the lever and maintain the 110 lever released and the circuit open.

WILLIAM J. BUECHLER.
